UNITED STATES PATENT OFFICE

129,591

DESIGN FOR A COFFEE MAKER

Richard F. Krause, Massillon, and Onnie Mankki,
Cleveland, Ohio, assignors to The Enterprise
Aluminum Company, Massillon, Ohio, a corporation of Ohio

Application April 19, 1940, Serial No. 91,778

Term of patent 3½ years

To all whom it may concern:

Be it known that we, Richard F. Krause and Onnie Mankki, both citizens of the United States, residing respectively at Massillon, in the county of Stark and State of Ohio, and at Cleveland, in the county of Cuyahoga and State of Ohio, have invented a new, original, and ornamental Design for a Coffee Maker, of which the following is a specification, reference being had to the accompanying drawing, forming part thereof.

Fig. 2 is a top plan view of the handle of the coffee maker shown in Figure 1; and

Fig. 3 is an elevational view of the inner side of the handle.

The body portion of the coffee maker is of circular contour throughout.

We claim:

The ornamental design for a coffee maker, as shown and described.

RICHARD F. KRAUSE.
ONNIE MANKKI.
